UNITED STATES PATENT OFFICE.

LEO EHRLICH, OF ST. LOUIS, MISSOURI, ASSIGNOR TO THE AMERICAN ROLL PAPER COMPANY, OF SAME PLACE.

PAPER-CUTTER.

SPECIFICATION forming part of Letters Patent No. 393,629, dated November 27, 1888.

Application filed April 23, 1888. Serial No. 271,505. (No model.)

To all whom it may concern:

Be it known that I, LEO EHRLICH, of the city of St. Louis, in the State of Missouri, have invented a certain new and useful Improvement in Paper-Cutters, of which the following is a full, clear, and exact description, reference being had to the accompanying drawings, forming part of this specification, and in which—

10 Figure I is a front elevation. Fig. II is an end view. Fig. III is an end view showing a modification. Figs. IV to IX, inclusive, are enlarged sections and detail views illustrating different parts.

15 My invention relates to an improvement in paper-cutters; and my invention consists in features of novelty hereinafter fully described, and pointed out in the claims.

Referring to the drawings, 1 represents a 20 suitable base, to which ends 2 are secured.

3 represents the roller journaled in the ends and upon which the paper 4 is wound.

5 represents arms secured to a cross-piece, 6, by means of boxes 7, and which are connected to the cross-piece by means of springs 8, which act to press a rod or bar on the lower ends of the arms against the roll of paper.

9 represents the rod secured to the lower 30 ends of the arms 5, and which is held against the roll of paper, as stated, by means of the spring-arms 5. Secured to the ends of this rod 9 are blocks 10, to one of which a roller, 12, is secured by means of a bracket, 13, (see 35 Fig. VI.) held upon the block by means of the knife-bar, which has collars 14. The other end of the roller is connected to the other block, 10, by means of a square nut, 15, (see Fig. VIII.) fitting in the block, and held 40 therein by a plate, 16, pivoted to this block at 17.

Secured to the blocks is a knife composed 45 of a square bar, 20, having end pieces, 21, by which it is secured to the blocks. The paper passes in between the bar 9 and the roller 12, as shown in Figs. IV and V, its end projecting, as shown at 22. When a piece of paper is wanted, it is drawn out and cut off against the knife, as shown in Fig. I.

50 On the roller 12 is an eccentric, 27, near the middle of the roller, and which presses

the paper against the rod 9 and prevents the backward turning of the paper roll. On the roller is also a weight, 23, which acts to force the part 27 against the rod 9. When the 55 end of the paper is to be inserted between the rods 9 and 12, the free end of the roller 12 is dropped down, as shown by dotted lines, Fig. I, by swinging the catch-plate 16 outward into the position shown by dotted lines, Fig. IX. 60

The rod 9 may be supported on different arms to those upon which the roller 12 is supported, as shown in the modification, Fig. III.

I reserve the right to claim in another application, Serial No. 271,507, filed April 23, 65 1888, a construction whereby one of the rods can be swung away from the other by mounting the rods on different arms.

I claim as my invention—

1. In a paper-cutter, the combination of the 70 ends, roller journaled in the ends, spring-arms, rod secured to the spring-arms, block secured to the rod, a rod secured in the blocks, and knife, substantially as and for the purpose set forth.

2. In a paper-cutter, the combination of the 75 ends, roller journaled in the ends, spring-arms, rod 9, secured to the spring-arms, a rod pivoted at one end to the rod 9 and secured to the rod 9 at the other end by means of a suitable catch, and knife secured to the rod 9, substantially as and for the purpose set forth.

3. In a paper-cutter, the combination of the 80 ends, roller journaled in the ends, spring-arms 5, rod 9, secured to the spring-arms, blocks secured to the rod 9, a rod secured in the blocks, and eccentric on the rod, substantially as and for the purpose set forth.

4. In a paper-cutter, the combination of the 85 ends, roller journaled in the ends, spring arms, and rod secured to the lower ends of the arms and having an eccentric, substantially as and for the purpose set forth.

5. In a paper-cutter, the combination of the 90 roll of paper, knife, and arms for supporting the knife, the knife consisting of a square bar bent to secure it to its supporting-arms, substantially as and for the purpose set forth.

LEO EHRLICH.

In presence of—

JOS. WAHLE,
EDWD. S. KNIGHT.
